MANUAL DATA ENTRY KEYBOARD CONSOLE

Rae F. Tankard, Owego, N.Y., assignor to International
Business Machines Corporation, New York, N.Y., a cor-
poration of New York

Filed Feb. 6, 1964, Ser. No. 78,543

Term of patent 14 years

(Cl. D26—5)

FIG. 1

FIG. 2

FIG. 3

FIG. 4

FIG. 5

FIG. 6

FIG. 1 is a front perspective view of a manual data entry keyboard console showing my new design;

FIG. 2 is a top plan view;

FIG. 3 is a front elevational view;

FIG. 4 is a rear elevational view;

FIG. 5 is a right side elevational view; and,

FIG. 6 is a left side elevational view thereof.

The dominant features of my design reside in those portions shown in full lines on the drawing.

I claim:

The ornamental design for a manual data entry keyboard console, as shown and described.
